UNITED STATES PATENT OFFICE.

CHARLES HENRY WILSON, OF JERSEY CITY, NEW JERSEY.

AXLE.

SPECIFICATION forming part of Letters Patent No. 396,845, dated January 29, 1889.

Application filed September 12, 1888. Serial No. 285,251. (No model.)

To all whom it may concern:

Be it known that I, CHARLES HENRY WILSON, of Jersey City Heights, in the county of Hudson and State of New Jersey, have invented a new and Improved Axle, of which the following is a full, clear, and exact description.

My invention consists of the construction, arrangement, and combinations of parts, all as hereinafter described and claimed.

Reference is to be had to the accompanying drawings, forming a part of this specification, in which similar letters of reference indicate corresponding parts in both the figures.

Figure 1 is a side elevation of my new and improved axle, and Fig. 2 is a sectional elevation of the same.

A B represent the two main sections of my new axle. These are united by the screw-shank A' of section A, being screwed into the internally-screw-threaded cavity B' of the section B. The outer surfaces of the central portions of the sections A B are screw-threaded, and upon them is screwed the coupling sleeve or tube C. This is prevented from movement by the collars a a, held in place by set-screw a' a'. Each section A B is formed with a bearing, D D', for the wheel, and back of this

bearing is formed the square portion E E', to which a wrench may be applied for separating the sections of the axle. When constructed in this manner, if one section should break it may be detached from the other and a new section put in place, thus obviating the necessity of losing the whole axle, as would be the case if made in one piece.

Having thus described my invention, what I claim as new, and desire to secure by Letters Patent, is—

An improved axle consisting of the two sections A B, each having their inner ends externally screw-threaded, the section A being provided with the reduced screw-threaded portion or shank A', and the section B with the internally-screw-threaded cavity B', to receive the said reduced portion or shank, and the internally-threaded sleeve C, fitting on the screw-threaded portions of the said sections, substantially as herein shown and described.

CHARLES HENRY WILSON.
